UNITED STATES PATENT OFFICE.

CLAYTON E. RICE, OF CHICAGO, ILLINOIS.

ADJUSTABLE LAMP-HOLDER.

1,241,150.

Specification of Letters Patent. Patented Sept. 25, 1917.

Application filed March 26, 1917. Serial No. 157,433.

To all whom it may concern:

Be it known that I, CLAYTON E. RICE, a citizen of the United States, residing at Chicago, in the county of Cook and State of Illinois, have invented certain new and useful Improvements in Adjustable Lamp-Holders, of which the following is a description, reference being had to the accompanying drawings, forming a part of this specification, in which corresponding numerals of reference in the different figures indicate like parts.

The primary object of my invention is to provide an adjustable lamp support which shall be simple, cheap and effective, for use upon automobiles, motor-boats and for other analogous purposes wherein a large range of adjustment and ready manipulation may be found desirable.

A further object is to so construct said device that the various manipulations may be made by means of a single handle or lever.

Moreover, it is my purpose to so utilize said lamp as to project light therefrom toward the rear of a vehicle for signal or other purposes in addition to that used in front, all of which is hereinafter more particularly described and definitely pointed out in the claims.

In the drawings,

Figure 1, is a plan of a lamp and an adjustable support therefor embodying the features of my invention,

Fig. 2, is an elevation thereof as it would appear when viewed from the side of a vehicle to which the same is attached,

Fig. 3, is a diagrammatic view of the electric lighting circuits and switches,

Fig. 3^a, is a sectional view in plan showing a modified construction,

Fig. 4, is a section taken upon the line 4—4, Fig. 2, viewed in the direction of the arrows there shown,

Fig. 5, is a section in plan taken upon the line 5—5, Fig. 4, viewed in the direction of the arrows there shown; and

Fig. 6, is a section taken upon the line 6—6, Fig. 4, viewed as indicated by the arrows.

Referring to the drawings, 1 indicates a main casing or stationary support, which may be rigidly connected to any suitable part of a vehicle, such, for example, as the standard 2, of an automobile wind-shield, shown in Fig. 1, and indicated in dotted

lines in Fig. 2, by means of a bracket 3, Figs. 1, 2 and 4; detachably secured thereto by a bolt 4 and attached to the part 2 by clamping members 5, 6 and bolts 7. In the example illustrated, the stationary part 1 has a vertical bore in the bottom thereof in which is journaled a tubular member 8, having a crank-arm 9 formed thereon for the purposes hereinafter set forth. Said tubular member is projected below the stationary casing and has rigidly clamped thereto a sleeve member 10 having a vertical slot 11, Fig. 6, formed therein and provided with rearwardly and downwardly extended arms 12, arranged parallel to each other upon opposite sides of said slot, the upper portion being connected by means of a bolt 13, Figs. 1, 2 and 6, to enable said sleeve to be rigidly clamped to the part 8. Projected between the arms 12 and into the sleeve 10 is the forward end 14 of a handle or operating lever 15, which is pivotally connected with said arms by means of a bolt 16 forming a fulcrum for the lever.

The tubular portion 8 forms a vertical axis for the handle, a lateral movement of which serves to actuate the crank arm 9, in one or another direction in a horizontal plane. By means of the construction shown, it will be seen that the lever has both a horizontal and vertical axis, the purposes of which will be presently explained.

Extending laterally from the casing 1, is a rocking member 17 journaled in such casing upon a horizontal axis. The journaled portion 18 has a crank member 19 rigidly attached to its inner end. A wrist-pin 20, is connected by means of a pitman 21, to the short end 14, of the handle lever through a bifurcated connecting member 22 and bolt or pin 23. The rocking member 17 has thereon an enlarged laterally extended casing 24, Figs. 2, 4 and 5, the upper portion of which is provided with a vertical bore in which is journaled a standard 25, which is rigidly formed upon, or connected with, a lamp casing 26, for which it forms a pivotal support. A crank-arm 27 is rigidly attached to the pivotal portion or lower end of the standard 26, which arm is connected by means of a pitman 28, to a wrist-pin 29 upon the crank arm 9. A swivel 28^a is interposed in the pitman 28, to enable the part 24 to be oscillated without injury to said pitman.

The casing 26 is intended to contain two

electric lamps of any well known construction, one of which, 30 indicated in dotted lines in Fig. 2, is intended to project light in front and the other, 31, is intended to project light toward the rear. The lamp 31 is separated from the lamp 30 by means of a partition 32 in the casing. The lamp 30 is connected by means of wires 33, 34 indicated in dotted lines in Fig. 2 and shown 10 in full lines in Fig. 3, with a source of electric energy 35, while the lamp 31 is connected therewith by means of wires 36 and 37. All of said wires are led through the casings and tubes respectively as indicated 15 in dotted lines in Fig. 2, to and through conduits or passages in the handle lever where the wires 33 and 34 are connected with the terminals of an electric switch 38 and the wires 36 and 37 with those of a switch 39. 20 In order that the handle lever may not become accidentally misplaced when not held by the user, I tighten the nut on the bolt 16, so as to cause a sufficient degree of friction upon the lever to hold it against abnormal 25 displacement.

For a like reason, I interpose between the stationary part 1 and the upper end of the sleeve member 10, a spring washer 10^a which should be under sufficient compression to 30 frictionally resist the rotation of the sleeve and hold it against accidental movement.

In the example illustrated I have contemplated using both lamps for what are commonly known as "spot-lights", or in 35 other words, for search-lights or for signal purposes; in which cases both of the switches indicated would be normally open, but it is obvious that one or both may be normally closed.

40 The operation of the apparatus is as follows: The lamp casing may be tilted so as to throw the lights up or down by merely tilting the handle-lever vertically upon the fulcrum pivot 16, when the pitman 21, acting upon the crank-arm 19, will cause the casing or rocking member, to be tilted upon a horizontal axis, thereby carrying with it the normally vertical lamp support 25. A lateral movement of the lever in turn serves 45 to actuate the crank-arm 9 which, through the pitman 28 and crank-arm 27, results in moving the lamp upon said normally vertical axis to throw the light rays laterally in either direction. These movements may be 50 varied indefinitely so as to impart a sufficiently universal movement to the lamp to meet all requirements of the user.

If used upon an automobile at night, the operator may so manipulate the lamp 30 as 55 to light the road while turning curves, ascending or descending hills, for reading signs, or for any similar purpose; while, by closing the switch 39, the light 31 may be directed toward the rear as a warning or 60 to enable the driver to see what is behind.

The advantage of being able to throw either light on or off and to direct them wherever desired by means of a single operating handle, is too obvious to require special comment.

70 In Fig. 3^a I have shown a modified construction in which the horizontal rocking member 40 is journaled in a stationary support 41, and is provided with a casing 42 rigidly attached thereto, in which an operating lever 43 is pivoted upon a vertical axis and arranged to swing laterally in a horizontal slot 44. The short end of the lever is jointedly connected to a rod 45 having a rack 46 upon its opposite end adapted to engage a pinion 47 keyed to the vertical lamp support. One advantage of this construction is that it enables certain connecting parts to be dispensed with without varying the fundamental principle, but in actual 80 practice I prefer that first described.

85 The operating handle is intended to be located near the steering wheel of an automobile and within the curtained inclosure, or that of an armored vehicle, so as to be 90 readily accessible under all conditions. I do not wish to be limited to the exact construction shown inasmuch as it is capable of variation without departing from the principle of the invention.

95 Having thus described my invention, I claim:

1. An adjustable device of the class described, comprising, in combination, a stationary support, a tubular rocking member 100 journaled therein upon a horizontal axis, a lamp directly supported upon said rocking member upon a pivotal support the axis of which is at right angles to that of said tubular member, an actuating lever arranged to tilt said rocking member while free to be moved upon an axis at right angles to that of the latter and movable connecting means for operatively connecting said pivotal support with said lever. 105

2. An adjustable device of the class described, comprising, in combination, a stationary support, a tubular rocking member journaled therein upon a horizontal axis, a lamp directly supported upon said rocking member upon a pivotal support the axis of which is at right angles to that of said tubular member while its end is extended into the hollow thereof, an actuating lever arranged to tilt said rocking member while free to be moved upon an axis at right angles to that of the latter and movable connecting means for operatively connecting said pivotal support with said lever, a portion at least of said connecting means being inclosed within said tubular rocking member. 115 120

3. An adjustable lamp-holder comprising, in combination, a stationary support, a rocking member journaled therein upon a hori- 125 130

- zontal axis, a lamp having a normally vertical support journaled in said rocking member upon an axis substantially at right angles to that of said rocking member, a tubular member swiveled in said stationary support, the axis of said tubular member being at right angles to that of said rocking member, an actuating lever fulcrumed on said tubular member with its short end therein to 10 permit a vertical and lateral movement of said lever, a crank-arm upon the lower end of said vertical lamp support, a crank-arm upon the end of said tubular member, a pitman for connecting said crank-arms and a 15 crank-arm upon the inner end of said rocking member in operative connection with the short end of said actuating lever.
4. An adjustable lamp-holder comprising, in combination, a stationary support, a tubular rocking member journaled therein upon a horizontal axis, a lamp having a support journaled in said rocking member upon a normally vertical axis, a tubular member swiveled in said stationary support upon a 20 vertical axis, an actuating lever fulcrumed upon a horizontal axis supported by said tubular member with the short end of said lever extending into said tubular member, means for connecting the short end of said 25 lever with said rocking member to oscillate the same, and means for connecting said tubular member with said normally vertical lamp support.
5. An adjustable lamp holder for imparting movement to a lamp in varying directions by means of a single actuating lever,

comprising a support, a rocking member journaled therein upon a horizontal axis, a lamp having a support journaled in said rocking member, the axis of the two being 40 at right angles to each other, a tubular lever supporting member journaled with its axis at right angles to that of said rocking member, an actuating lever pivoted upon a horizontal axis in said lever supporting member, connecting means between one end of said lever and said rocking member and connecting means between said lamp support and tubular lever supporting member.

6. An adjustable lamp holder comprising, 50 in combination, a stationary support, a tubular rocking member journaled therein upon a horizontal axis, a lamp having a support journaled in said rocking member upon a normally vertical axis, a tubular member 55 swiveled in said stationary support upon a vertical axis, an actuating lever fulcrumed upon said tubular member with its short end extending therein, means for connecting the same with a crank-arm upon said rocking 60 member, a crank-arm upon the upper end of said tubular member, a crank-arm upon the lower end of said normally vertical lamp support and means within said rocking member for connecting said crank-arms.

In testimony whereof, I have signed this specification in the presence of two subscribing witnesses, this 22d day of March 1917.

CLAYTON E. RICE.
